(57) **CLAIM**

We claim the ornamental design for programmable controller, as shown and described.

DESCRIPTION

FIG. 1 is a front view of programmable controller showing the new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof; and,

FIG. 7 is a perspective view thereof.
